[57] CLAIM

The ornamental design for a ceiling fan unit, as shown and described.

DESCRIPTION

FIG. 1 is a side elevational view of a ceiling fan unit, showing my new design, the opposite side being a mirror image of that shown;

FIG. 2 is a bottom plan view thereof;

FIG. 3 is a side elevational view of a ceiling fan unit, showing a second embodiment of my new design with the lighting fixture omitted, the opposite side being a mirror image of that shown;

FIG. 4 is a bottom plan view of FIG. 3; and

FIG. 5 is a top plan view of FIGS. 1 and 3.

FIG. 3

FIG. 4

FIG. 5
